O. L. GARDNER, OF NEW YORK, N. Y.

Letters Patent No. 89,139, dated April 20, 1869.

IMPROVED ADJUSTABLE CORNICE FOR WINDOW-CURTAINS.

The Schedule referred to in these Letters Patent and making part of the same.

To all whom it may concern:

Be it known that I, O. L. GARDNER, of New York, in the county of New York, and State of New York, have invented a new and useful Improvement in Window-Cornice; and I do hereby declare that the following is a full, clear, and exact description thereof, which will enable others skilled in the art to make and use the same, reference being had to the accompanying drawings, forming part of this specification.

This invention relates to a new and useful improvement in cornices for supporting window-curtains in dwellings and other buildings, the improvement having reference to a mirror-frame, for which Letters Patent were granted me, dated September 10, 1867, the cornice being intended as a continuation of the moulding of the said frame, in completing the finishing of the room, but which cornice may be used separately therefrom.

In the accompanying plate of drawings—

Figure 1 represents the cornice connected with a mirror-frame, the window being shown in red color;

Figure 2 is a sectional top view; and

Figure 3 is a sectional back view of the cornice, showing the method of rendering it adjustable to suit windows of different widths.

Figure 4 is a cross-section of fig. 3 through the line *xx*.

Similar letters of reference indicate corresponding parts.

A is the cornice.

This cornice is made adjustable, so that it may be fitted to windows of different widths.

When the mirror-frame is used, the adjustable cor-

nice may be fitted thereto, so that the arch of the frame may form a central and leading feature in the apartment-cornice.

This cornice is made adjustable by means of slots in the back of the central projections B, as seen in fig. 3.

C C are screws, which are attached to the parts D D, each side of the centre, and which work in the slots, as the parts are drawn from or pushed toward the centre.

The front projection, B, and the back, E, are connected together by the cross-piece F, so that the central part of the cornice remains stationary.

The cornice may be made adjustable at the end projection G G, by the same or similar arrangement, if desired, but I have found the present method most convenient.

The cornice may be made adjustable at both ends, and also at the centre, so that it may be extended a foot or more, and still preserve its symmetry and true architectural proportions.

Having thus described my invention,

I claim as new, and desire to secure by Letters Patent—

Making the cornices of windows adjustable, substantially as and for the purposes herein shown and described.

The above specification of my invention signed by me, this 9th day of February, 1869.

O. L. GARDNER.
